UNITED STATES PATENT OFFICE.

EDWIN D. TILLSON, OF EVANSTON, ILLINOIS.

LIGHTING DEVICE.

1,360,825.

Specification of Letters Patent. Patented Nov. 30, 1920.

Application filed May 21, 1919. Serial No. 298,706.

To all whom it may concern:

Be it known that I, EDWIN D. TILLSON, a subject of the King of Great Britain, residing at Evanston, in the county of Cook 5 and State of Illinois, have invented a certain new and useful Improvement in Lighting Devices, of which the following is a specification.

My invention relates to lighting devices, especially those employing higher powered lamps, for example, 500 watt nitrogen filled lamps in which the filament is usually quite concentrated and consequently is apt to produce disagreeable images in the associated 10 reflector. The object of the invention is to produce a fixture which will utilize to the fullest extent the energy used for producing the light and at the same time protect the eyes of those within range. It is also my 15 object to provide details of construction which contribute to the general efficiency of the device. Among these details are: A convenient hanger for suspending the translucent element and convenient means for suspending the deflector blades near the lower 20 part of the structure.

I obtain my objects by the structure illustrated in the accompanying drawings in which—

30 Figure 1 is an elevation of the complete device, chiefly in central or axial section.

Fig. 2 is a bottom plan view omitting the reflector.

35 Fig. 3 is a fragmentary side elevation showing the dropped position of the deflectors.

Fig. 4 is a top plan section on the line 4—4 Fig. 1.

40 Fig. 5 is a perspective view of the hook-shaped hanger employed for suspending the translucent elements.

Like numerals denote like parts throughout the several views.

In the form shown in the drawings for illustrating the principle of the invention, 45 the light source 1 is a filament mounted within a bulb 2 which screws into a socket 3 in accordance with standard construction. It may be assumed that the bulb and filament are parts of a high powered nitrogen filled lamp. The socket 3 is stationary and is supported by any suitable means, said means also supporting the stationary reflector 5. Ordinarily, said reflector will be comparatively flat, as shown, thus spreading the 55 light over a considerable area.

Beneath the reflector is a translucent ele-

ment which according to the present design, has a cylindrical portion 6 and an upper portion 7. The portion 7 is of very light density, converges upward and inward, and is located in position to intercept and diffuse the rays directed toward the reflector. It will be understood that in high powered lamps, like those previously mentioned, the filaments are ordinarily quite concentrated 65 with the result that the reflected rays present to the eye an image of the filament, and this is so bright that it is disagreeable if not injurious. In my device the upper portion 7 is of such light density that the 70 rays will not be appreciably dimmed but simply diffused enough to prevent the reflector from showing an image of the filament. The action is illustrated by the ray A, Fig. 1, and the diffused rays A¹. The 75 portion 6 of the translucent element is of greater density. In practice, for commercial and manufacturing reasons, the increase in density is produced by simply firing a band 8 of enamel onto the outside of the 80 portion 6 which is otherwise of the same character as portion 7.

While the vertical dimensions of the cylindrical portion of the translucent element may be varied, it may be stated in general 85 that its elevation at the center is about the same as the elevation of the filament, the upper edge being high enough to intercept the rays which would otherwise escape the lower edge of the reflector, and the lower 90 edge being low enough to confine the direct rays to a moderate size circle beneath the lamp.

The translucent element is suspended by hangers here shown in the form of hooks 95 10 shown in perspective in Fig. 5. The hooked lower end engages the lower edge of the translucent element, and the upper end is yieldingly supported by leaf springs 11, 11 adapted to rest upon the top of the reflector as shown near the center of Fig. 1. The result of this construction is that the translucent element is held snugly in contact with the reflector and hence there is no vibration—a characteristic of considerable advantage in factory buildings where the machinery produces a constant and sometimes considerable vibration of the building. This type of suspension has another advantage in that when the translucent element is removed, the hangers automatically swing inward toward the vertical 100 105 110

axis of the device, thus facilitating re-hanging and removal of the translucent element. The position of the hangers when not in active position is indicated by the dotted lines at the left of Fig. 1.

While the cylindrical element 6, 8 is translucent, nevertheless, with high powered lamps and concentrated filaments an image is formed on the inside of it which would be visible and hence a source of annoyance to a person standing even at a considerable distance. For example, a ray such as the one indicated by B, Fig. 1, would be reflected as shown by the ray B¹, and this would be visible within quite an area surrounding the lamp. In my device, this disagreeable effect is prevented by means of deflectors 14. These are arranged in vertical planes located in the opening at the lower edge of the translucent member. They are located beneath the lamp, but by preference are so formed as to follow the contour of the lamp around the bottom portion thereof. According to the present design there are three of these deflectors and they are so positioned that they will intercept the rays (as B¹, Fig. 1) which would otherwise form an image of the filament. These deflectors, being arranged in vertical planes, will practically cause no shadows directly beneath and they will not cause any perceptible shadows in a lateral direction for the reason that the areas which might be shadowed by them will be lighted either directly or by reflection from some other part of the device. In the preferred construction the deflectors are attached to the lower end of the hangers 10. To facilitate removal of the lamp without disturbing the translucent element, it is desirable that the pin 15, shown at the left of Figs. 1 and 3 be a permanent pivot pin, the other pins 16, 16 being removable to permit the deflectors to swing down about the pin 15 as a pivot. The dropped position of the deflectors is indicated in Fig. 3.

In practice, when the parts are assembled

as shown in Fig. 1, the rays passing upward toward the reflector will, most of them, first pass through the portion 7 of the translucent element and be diffused sufficiently to prevent the formation of an image on the reflector, but without being dimmed to any appreciable extent. The rays which are directed horizontally or somewhat below the horizontal are in part transmitted and in part reflected by the portion 6, 8 of greater density. However, the image which is formed on the inner surface of the portion 6 is intercepted by the deflectors and by them reflected. By the time the light reaches the eye of an observer in almost any position relatively to the device as a whole, it will be so broken up and diffused that it will be, as it were, homogeneous and therefore create a pleasing impression and at the same time take full advantage of the electric energy consumed in the filament.

Having thus described my invention what I claim as new and desire to secure by Letters Patent, is:

1. A lighting device having a light source, a reflector above said source, and a translucent element on the general level of the light source and extending up approximately to the reflector, said element being open at the bottom and the lower portion being of considerable density, the upper portion being of very light density for partially diffusing the rays directed toward the reflector.

2. A lighting device having a light source, a reflector above said source, a translucent element surrounding said source, said translucent element being open at the bottom, and hooks suspended from the reflector and adapted to engage the lower edge of the translucent element, said hooks being yieldingly supported whereby they tend to press upward upon the translucent element and hold it in close contact with the reflector.

In witness whereof I have hereunto subscribed my name.

EDWIN D. TILLSON
